UNITED STATES PATENT OFFICE.

ISAAC J. F. KING, OF ASBURY PARK, NEW JERSEY.

DESIGN FOR A CUP OR SIMILAR ARTICLE.

40,417.

Specification for Design.

Patented Dec. 28, 1909.

Application filed November 2, 1909. Serial No. 525,968. Term of patent 7 years.

To all whom it may concern:

Be it known that I, ISAAC J. F. KING, a citizen of the United States, residing at Asbury Park, in the county of Monmouth and State of New Jersey, have invented a new, original, and ornamental Design for Cups or Similar Articles, of which the following is a specification, reference being had to the accompanying drawing, forming part thereof.

The figure is a plan view of a cup, showing my new design.

I claim:

The ornamental design for a cup or similar article, as shown.

ISAAC J. F. KING.
